UNITED STATES PATENT OFFICE.

KARL KIEFER, OF CINCINNATI, OHIO.

DISPENSING DEVICE.

Application filed December 26, 1919. Serial No. 347,474.

To all whom it may concern:

Be it known that I, KARL KIEFER, a citizen of the United States, residing at Cincinnati, in the county of Hamilton and State of Ohio, have invented certain new and useful Improvements in Dispensing Devices, of which the following is a specification.

My invention relates to filling machines or other dispensing devices, and its object is to dispense to individual ones of a plurality of containers substantially uniform amounts, either operating in conjunction with a filling machine to place relatively small amounts of substance in each container along with the principal substance either previously or subsequently placed in the containers by means of the filling machine, or else operating alone or in conjunction with devices other than filling machines.

In the drawings:

Fig. 1 is a partial plan view of a filling machine equipped with an improved dispensing device according to my invention, the containers being represented by dotted lines only, to avoid confusion;

Fig. 2 is a partial side elevation of the same, the containers being shown by full lines;

Fig. 3 is a partial vertical sectional elevation on a plane corresponding to the line 3-3 of Fig. 1;

Fig. 4 is a partial vertical section on a plane corresponding to the line 4-4 of Fig. 1; and

Fig. 5 is a detail side elevation of the discharge controlling plug.

The filling machine in conjunction with which I prefer to use my improved dispensing device, and which is partially illustrated herein, is constructed substantially according to my invention as disclosed and claimed in my Patent No. 1,313,301, issued August 19, 1919, and in my co-pending application Serial No. 278,287, filed February 20, 1919.

In this machine, as shown herein, there is a carrier frame comprising outer and inner parallel bars 1 and 2 along opposite sides of the machine joined by corresponding bars 3 and 4 extending around in a semi-circle at one end of the machine. Carriers 5 are caused, by suitable mechanism not shown, to travel along the bars 1 and 2 at

one side toward the semicircular end bars 3 and 4, and therearound to the bars 1 and 2 at the opposite side, where the carriers 5 travel in the opposite direction to the other end of the machine and there are carried around by suitable mechanism, so that these carriers travel continuously around the machine. The mechanism referred to comprises sprocket wheels and a chain 6 that carries the carriers, one of these wheels being understood as being concentrically fixed to the upright shaft 7. Thus, these carriers 5 are caused to travel in unison with the rotation of this shaft 7, passing around the curved end of the machine in regular succession. The purpose of my invention is to discharge moderate amounts of liquid into containers carried by these carriers, from a stationary means but with the containers moving continuously.

Above the carriers 5 is the filling head, comprising the upper distributing element 8 held stationary by an arm 9 carried thereby engaging a column 10 fixed in the machine frame between the parallel carrier-frame bars, and a discharging element 11 making close contact with the lower side of the distributing element 8 and keyed to and rotated with the shaft 7. These elements 8 and 11 are held together by a nut 12 screwed on the threaded upper end part of the hub 13 of the rotatable discharging element 11, which extends up through the hub 8' of the stationary distributing element 8, with a collar 14 having a key 14' in the hub 13, between the nut 12 and the top of the hub 8'. This filling head is held at any desired height on the shaft 7 by a nut 15 screwed up on the shaft against the bottom of the discharging element 11 and a lock-nut 15' screwed down on the shaft against the top of the hub 13 where this hub extends slightly above the nut 12. The distributing element 8 has the segmental channel 16 receiving substance from the conduit 17, leading from supplying means not shown, and discharging to successive openings 18 in the rotary discharging element 11 as the openings are brought around in the rotation.

The machine is so arranged that the containers receive uniform amounts of substance. These purposes are accomplished by virtue of the operation of the machine as fully described in the patent and the application hereinbefore referred to.

The improved dispensing device making up the present invention will now be described.

A receiving cup 19 and a discharging cup 20 are mounted side by side by having a bracket 21 bolted to a bracket 22 which is clamped upon the lower part of the column 10. These parts are so proportioned and arranged that the discharging cup 20 will have one of the containers A' under it about the time or shortly after the discharge from the filling head begins into the container A on the next preceding carrier 5. The receiving cup 19 is disposed diagonally from the cup 20 over toward the column 10 with a substantial space separating the two cups; but preferably these two cups 19 and 20 and their bracket 21 are cast integral.

The receiving cup 19 has an outlet 23 opening from its bottom into a port 24 that runs in the casting in an upwardly inclined direction into the side of the discharging cup 20 next to the bottom thereof. Preferably this port 24 is left open at one end for facilitating its cleaning and is normally closed by a plug 25 screwed into said end. The upper part of the opening 23 is in the form of a conical valve seat 26. The measuring plug 27 of elongated cylindrical formation has its lower end adapted to fit into the seat 26 and slides up and down in a guide 28 which comprises a central hub with diverging arms 29 lying against the walls of the upper part of the receiving cup 19 and resting on an annular shoulder 30 formed on the interior of the cup near its bottom. The upper end part of this plug 27 has a vertical slot cut down from its top so that it is bifurcated and a roller 31 lies in this slot between the members of the plug and is journaled on a pin 32 passing transversely through these members.

The discharging cup 20 has an opening 33 in its bottom in the form of a conical valve seat and the discharge-controlling plug 34 is of elongated cylindrical formation with a conical pointed lower end 35 fitting into the seat 33. This plug 34 has longitudinal grooves 36 at opposite sides opening through this conical end 35 and leading up to an annular groove 37 extending entirely around the plug, from which further short longitudinal grooves 38 lead upward at opposite sides half way between the grooves 36. The upper end part of this plug 34 has a vertical slot cut down from its top, as in the plug 27, and a roller 39 lies in this slot and is journaled on a pin 40 passing therethrough. This discharge-controlling plug 34 slides up and down in a bushing 41 that has its upper part threaded and screwed down in the threaded interior of the upper part of the cup 20. The lower part of the bushing 41 is smooth and fits in the smooth lower part of the interior of the cup 20.

The upper end of the bushing 41 has the hexagonal head 42 for grasping the bushing to screw it up and down in the cup to vary the capacity of the cup; and a lock nut 43 is screwed onto the bushing, under 70 the head 42, to clamp down against the rim of the cup and fix the bushing in its adjusted position.

Between the two cups 19 and 20 there is an upstanding fork 44 in which is pivoted 75 a rocker 45 with one end 46 projecting into the slot under the roller 31 of the measuring plug 27, and another end 47 projecting into the slot under the roller 39 of the discharge-controlling plug 34. This rocker 45 also has 80 an upward projection which has an upwardly opening recess 48.

An outer collar 49 is clamped around the collar 14 by means of the set screws 50; the collar 14 being keyed to the hub 13 as before 85 described, so that the collar 49 turns with the filling head. In the periphery of the collar 49 is a series of pins 51 with circumferentially sloped projections 52. An arm 53 is clamped to the column 10 above the 90 bracket 22 and extends over the filling head close to the collar 49. A bell-crank lever has its fulcrum 54 in this arm near its end next to the collar 49, and comprises a long arm 55 engaging in the recess 48 of the rocker 95 45, and a shorter arm 56 extending out on the opposite side of the fulcrum and connected to the part of the arm 53 near the column 10 by a tension spring 57. This bell-crank lever also comprises another arm 100 58 near the fulcrum 54 over alongside the collar 49 and having on its end a fork 59 which opens toward the collar and has between its members a roller 60 which is held against the periphery of the collar 49 yield- 105 ably by action of the tension spring 57 on the bell-crank lever. Each time a projection 52 passes this roller 60 the bell-crank lever will swing its long arm 55 over toward the receiving cup 19, so tilting the 110 rocker 45 that the measuring plug 27 in the receiving cup will be lowered and the discharge-controlling plug 34 in the discharging cup will be raised; this arm 55, in its opposite position when the roller 60 is bearing 115 against the periphery of the collar 49, having raised the measuring plug 27 and lowered the discharge-controlling plug 34. The collar 49 may be adjusted around on the collar 14 to exactly time this operation to the 120 travel of the containers A; the set screws 50 being loosened for the adjustment, and then tightened to fix the collar 49 in its newly adjusted position.

The receiving cup 19 has an inlet 61 in its 125 bottom up into which leads a flexible hose or conduit 62 from a supply cup 63 receiving the neck 63' of the inverted reservoir 64 (represented diagrammatically in Fig. 3), so arranged that, due to partial vacuum within 130

the reservoir 64 above the liquid therein and atmospheric pressure through the opening 63" of the cup 63 on the surface of the liquid in the cup 63, it keeps the supply cup 63 and receiving cup 19 supplied with the liquid to any desired constant level B, which is the level of the end of the neck 63', and which level in the cup 19 may be determined by placing the cup 63 and reservoir 64 at the required height on the standard 64'. Each time the measuring plug 27 rises, this liquid flows through the outlet 23 and the port or passage 24, rising into the space at the bottom of the discharging cup 20 below the bushing 41 and in the narrow vent grooves 36 to the level B. The outlet 33 is at this time closed by the lowering of the discharge-controlling plug 34. Then when one of the projections 52 swings the bell-crank lever as before described, lowering the measuring plug 27 and raising the discharge-controlling plug 34, a definite amount of the liquid is cut off from the main body in the receiving cup by the closing of the valve 25 constituted by the conical lower end part of the plug 27 seating on the valve seat 26; and at the same time the valve constituted by the pointed lower end part of the plug 34, seating in the outlet 33, is opened, and the definite amount of liquid flows out through the outlet 33 and around the pointed end of the plug 34. The vent grooves 36, 37 and 38 permit escape of air from the space below the bushing when liquid is admitted thereto, and permit inflow of the air so that the liquid will flow therefrom. Their abruptly changing course, afforded by placing the longitudinal grooves out of alignment, avoids splashing of the inflowing liquid out of the upper ends of the grooves when suddenly admitted by the quick raising of the measuring plug 27 as before set forth. The pointed end of the plug 34 acts, by virtue of cohesion of the liquid, to concentrate the outflow so that it quickly drops into the container A' without scattering or spillage. The quick discharge obviates the necessity of stoppage of the container under it, or of having the device to move in unison with the container.

This device is especially suitable for discharging into containers small quantities of acid which it is desired shall be mixed with the principal substance filled into the container by the filling head, as was described. In any case, it is very simple, avoiding use of floats, plungers and the like, and relying merely on atmospheric pressure to afford practically uniform delivered charges.

The brackets 22 and arm 23 may be adjusted up or down on the column 10 when the filling head is raised or lowered for containers of different heights, by loosening and again tightening the clamping bolts 65. The bracket and arm are held the proper dis-

tance apart during such adjustment, by a spacing pin 66 set in the bracket 22 and extending up against the bottom of the arm 53.

It will be understood that my improved dispensing device may be used in conjunction with the filling machine described, or with other filling machines, or independently thereof, as conditions may require, and is also susceptible to various modifications in adapting it to different requirements. Therefore, having fully described my invention, what I claim as new and desire to secure by Letters Patent is:

1. In a dispensing device, a fixed receiving cup, a fixed discharging cup, said cups having a passage connecting the lower parts of their interiors, a valve controlling communication between said receiving cup and said passage, said discharging cup having an outlet, a valve controlling said outlet, operating means connected to said valves to alternately open said valves, rotary means bringing containers successively under said discharging-cup outlet, and an operative connection between said operating means and said rotary means.

2. In a dispensing device, a receiving cup and a discharging cup connected together, each having an outlet in its bottom and each having an inlet in its lower part, and having a passage connecting the outlet of said receiving cup with the inlet of said discharging cup, a plug extending down through the interior of said receiving cup into said outlet to close said outlet when lowered or to open said outlet when raised, a guide comprising a hub receiving said plug and means spacing said hub from the walls of said cup, a discharge-controlling plug extending down through the interior of said discharging cup into said discharging-cup outlet to close the outlet when lowered or to open said outlet when raised, a bushing adapted to be adjusted up or down in the interior of said discharging cup, around said plug, to vary the capacity of said cup adjacent to said discharging-cup inlet and outlet, a rocker operatively connected to said plugs to alternately raise and lower each plug as it lowers and raises the other plug, rotary means bringing containers successively under said discharging-cup outlet, a series of projections on said rotary means, and a lever operatively engaging with said rocker and operatively engaged by successive ones of said projections to rock said rocker.

3. In a dispensing device, a receiving cup and a discharging cup having a passage connecting the bottoms of their interiors, said discharging cup having an outlet in its bottom, valves controlling said passage and said outlet, respectively, a rotary filling head, a rotary carrier bringing containers successively under said discharging-cup outlet and

under said filling head, a mounting for said filling head whereby it may be adjusted up or down for containers of various heights, an operative connection from said rotary filling head to said valves whereby said valves are alternately closed, and a mounting for said cups whereby they may be adjusted up or down for said containers of various heights, and whereby said operative connection is maintained.

4. In a dispensing device, a receiving cup and a discharging cup having a passage connecting the bottoms of their interiors, said discharging cup having an outlet in its bottom, valves controlling said passage and said outlet, respectively, a rotary filling head, a rotary carrier bringing containers successively under said discharging-cup outlet and under said filling head, a mounting for said filling head whereby it may be adjusted up or down for containers of various heights, a series of projections rotating with said filling head, a rocker operatively connecting said valves together and alternatively opening and closing said valves, a lever operatively engaging with said rocker and operatively engaged by successive ones of said

rotating projections to rock said rocker, and a mounting for said cups and said lever whereby said cups may be adjusted up or down for said containers of various heights and whereby said lever is maintained in its position relative to said projections.

5. In a dispensing device, a fixed pair of chambers having an intercommunicating passage, means for adjusting the capacity of the space in one of said chambers adjacent to said passage, controlling means for controlling inlet from the other chamber through said passage, said space having an outlet, controlling means for controlling discharge from said space through said outlet, mechanism for alternately operating the two controlling means to alternately admit a substance into said space to be measured therein and discharge the measured substance from said space, carrying means continuously traveling carrying successive containers to said outlet of said space, and an operative connection between said mechanism and said carrying means whereby said controlling means are operated in unison with the carrying of the containers to said outlet.

KARL KIEFER.
